UNITED STATES PATENT OFFICE.

MAURICE C. RYPINSKI, OF YONKERS, NEW YORK, ASSIGNOR TO BRANDES LABORATORIES, INC., OF NEWARK, NEW JERSEY, A CORPORATION OF NEW JERSEY.

SOUND-REPRODUCING DIAPHRAGM.

Application filed January 7, 1926. Serial No. 79,845.

My invention relates broadly to sound reproducing diaphragms and more particularly to the construction of a conical shaped diaphragm.

5 One of the objects of my invention is to provide a conical shaped diaphragm having a sound reproducing surface which is not interfered with by a connecting seam which is generally present in conical diaphragms 10 heretofore available in electromagnetic sound reproducing devices.

Another object of my invention is to provide a conical diaphragm formed of a single integral sheet of material having one 15 portion thereof rigid for the reproduction of sound and a peripheral portion surrounding the rigid portion which is flexible or semi-rigid in order to permit movement of the sound reproducing surface as a whole.

20 Still another object of my invention is to provide a conical diaphragm which may be readily molded between two surfaces from material which is hardened throughout the central portion of the diaphragm and 25 treated to form a resilient peripheral portion around the central portion of the diaphragm.

A further object of my invention is to provide a construction of sound reproducing 30 diaphragm which may be readily molded from rubber and treated throughout its peripheral portion to secure a resilient peripheral flange integrally united with the rigid central portion thereof.

35 My invention will be more clearly understood from the specification hereinafter following by reference to the accompanying drawings, in which:

Figure 1 is a front view of the conical diaphragm of my invention; Fig. 2 is a 40 cross-sectional view taken on line 2-2 of Fig. 1; and Fig. 3 is an enlarged fragmentary sectional view taken on line 3-3 of Fig. 1.

45 Heretofore in the art in the construction of conical diaphragms for electromagnetic sound reproducers it has been customary to employ paper which is rolled into a conical shape and the adjacent edges secured together in a seam. In order to resiliently 50 mount such diaphragms it has been necessary to secure a flexible flange around the periphery of the paper diaphragm thus formed. This has usually been accomplished 55 by gluing a rubber strip around the periph-

ery of the paper cone. This construction has a number of inherent disadvantages and requires considerable labor in its manufacture. There are a number of steps required in assembling the paper material, punching the 60 material to size, forming the material over a conical pattern, subsequently gluing the seams of the material, and then providing a resilient circular flange for the peripheral support of such a diaphragm. In my present 65 invention I avoid all these manufacturing difficulties and in addition I provide a diaphragm of permanent construction. That is to say, the conical diaphragms of the prior art have been ineffective to the 70 extent that there is a tendency for the seam to spring or the peripheral flange tends to leave the peripheral edge of the paper cone, thereby destroying the effectiveness of the diaphragm.

75 In the present invention I provide a molded form of conical diaphragm where the material of the diaphragm may be pressed between two surfaces such as porcelain polished to provide a seamless cone. I 80 have found that rubber is particularly suitable for this use. I may however, employ a sheet of linen on which bakelite is deposited forming a bakelized linen conical surface. A part of this surface is treated to 85 secure a hardened central body portion for the cone. In the case of rubber, the central portion is vulcanized leaving a flexible or semi-vulcanized outer surface in the form of a circular flange which integrally connects with the vulcanized or hardened portion of the cone. In the case of bakelite only the central portion is treated to harden it leaving the outer peripheral portion flexible for the suspension of the central portion.

90 95 My invention will be more clearly understood by a detailed reference to the accompanying drawings as follows:

I have shown the central portion of the cone diaphragm as represented by reference 100 character 1 formed from the hardened rubber or bakelized linen. United to the body 1 I provide an annular rim portion 3 which is curved as represented at 2 and secured at its outer periphery between ring members 5 105 and 6. The portion 4 of the annular rim extends between the two ring members 5 and 6 forming a suspension for the remainder of the diaphragm. The ring members 5 and 6 are gripped together in suitable manner 110

such as by means of rivets 7, 8, 9, 10, 11, and 12. The flange portion 4, 2, and 3 of the annular rim is flexible and yet it is an integral portion of the body portion 1 of the diaphragm. In order to more clearly illustrate the difference between the characteristics of the flange portion 4, 2 and 3 and the body portion 1 of the cone I have shown in Figs. 2 and 3 cross-hatching in opposite directions to show that the central body portion 1 is formed of rigid material while the peripheral portion 4, 2 and 3 is formed of soft flexible resilient material integrally united with the body portion 1. It will be observed that there are no seams in the diaphragm construction of my invention and that accordingly there is no tendency for the diaphragm to change its condition during its period of use. The diaphragm is constructed for long life and at the same time the construction affords inexpensive manufacture and assembly. I have not illustrated a connection to the apex of the cone for an electromagnetic driver but it will be understood that apex pieces may be attached to the apex of the cone on opposite sides thereof and a connecting rod secured therethrough for connection to an electromagnetic driver.

While I have described my invention in certain particular embodiments, I desire that it be understood that modifications may be made and that no limitations upon the invention are intended other than those imposed by the scope of the appended claims.

What I claim and desire to secure by Letters Patent of the United States is as follows:

1. A sound reproducing diaphragm comprising in combination a conical shaped body portion, a resilient peripheral flange surrounding said body portion, and having elastic properties for allowing bodily movement of said body portion, said resilient peripheral flange being constructed of the same kind of material as the said body portion and integrally united therewith for forming a flexible suspension for said body portion.

2. A conical shaped diaphragm compris-

ing in combination a central body portion, a peripheral resilient flange surrounding said body portion and having elastic properties for allowing bodily movement of said body portion, said flange being integrally united with said body portion and forming a suspension for said body portion whereby said body portion is free to vibrate independently of said flange.

3. A conical shaped diaphragm comprising in combination a rubber sheet forming a central body portion, an annular rubber sheet connecting said central body portion and forming a suspension rim for said body portion, said body portion being vulcanized and said rim being left in a resilient state for the resilient suspension of the vulcanized rubber portion.

4. A conical shaped diaphragm comprising in combination, a central body portion, an annular rim portion integrally united with said central body portion, said central body portion being formed of vulcanized rubber and said annular rim portion being formed of rubber left in its resilient state for the flexible suspension of said vulcanized rubber portion.

5. A conical shaped sound reproducing diaphragm comprising in combination a central body portion, an annular rim integrally united with said central body portion, said central body portion being formed from vulcanized rubber and said annular rim portion being formed from soft rubber, whereby said rim portion retains its resilient characteristics for the flexible suspension of said vulcanized rubber portion.

6. A sound reproducing diaphragm comprising in combination a central body portion, an annular rim portion integrally united with said central body portion, each of said portions being molded from rubber and said central body portion being vulcanized for securing a hardened sound reproducing surface while leaving said annular rim portion in soft resilient condition for the flexible suspension of said central body portion.

MAURICE C. RYPINSKI.
